ATTORNEYS

UNITED STATES PATENT OFFICE.

AUSTIN F. JACKSON, OF TAUNTON, MASSACHUSETTS.

DESIGN FOR A SPOON, &c.

SPECIFICATION forming part of Design No. 21,513, dated May 3, 1892.

Application filed April 1, 1892. Serial No. 427,424. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for the Handles of Spoons, Forks, Knives, Ladles, &c., of which the following is a specification, reference being had to the accompanying drawing, forming part 10 thereof.

The figure is a front or upper face view of a spoon whose handle is provided with my design.

The leading feature of my design consists 15 in a representation in relief of a leaf and a spray of blossoms of the lily-of-the-valley, which leaf and spray form, with their outer edges, the marginal edge of the handle and impart their shape to the same.

A is the leaf, which extends from a stem B, 20 which forms the shank of the spoon. This leaf A extends to and forms the outer end of the spoon-handle, while upon the leaf, in nearly central position thereon, is a spray of blossoms C. This leaf, together with the blossoms and stem, form by their shape the outer edges or margin of the spoon-handle. 25

Having thus described my invention, what I claim is—

The design for the handle of a spoon, &c., 30 herein shown and described.

AUSTIN F. JACKSON.
